United States Patent [19]

Weber et al.

[11] Patent Number: Des. 305,534

[45] Date of Patent: ** Jan. 16, 1990

[54] MOBILE INPUT/OUTPUT DATA TERMINAL

[75] Inventors: Howard F. Weber, Springhill, Fla.; Donald E. Metivier, Denton, Tex.

[73] Assignee: ElectroCom Automation, Inc., Houston, Tex.

[**] Term: 14 Years

[21] Appl. No.: 37,575

[22] Filed: Apr. 13, 1987

[52] U.S. Cl. D14/100; D14/106

[57] CLAIM

The ornamental design for a mobile input/output data terminal, as shown and described.

DESCRIPTION

FIG. 1 is a top, left, front perspective view of a mobile input/output data terminal showing our new design;

FIG. 2 is a front elevational view thereof;

FIG. 3 is a rear elevational view thereof;

FIG. 4 is a top plan view thereof;

FIG. 5 is a bottom plan view thereof;

FIGS. 6 and 7 are respectively right and left side elevational views thereof.
